DEVICE FOR SUPPORTING TELEPHONE APPARATUS

Alvin N. Epstein, Chicago, Ill.

Application August 17, 1939, Serial No. 290,620

3 Claims. (Cl. 179—157)

This invention relates to a device for supporting telephone apparatus, and more particularly concerns a construction of this character which is designed for holding a combination receiver-transmitter telephone unit upon the shoulder of the user by pressure of the ear to the receiver and permit free use of the hands for other purposes.

The principal object of the invention is to provide a simple, convenient, and inexpensive device of the aforesaid character which may be easily applied to combination receiver-transmitter telephone units, which will not seriously hamper or interfere with the usual method of handling the same, and which may be employed by brokers, order-clerks, and others to permit a two-way telephone conversation to be carried on while the hands are free for making notations, consulting records, listing orders, etc.

While devices of this general character have been proposed for holding earlier forms of telephone receivers propped between the ear and shoulder of the user, and body and head harnesses are used by telephone switch-board operators for holding separate receiver and transmitter telephone units in position, such devices and harnesses are not suitable for the above-mentioned uses, since they either do not provide for the support of combination receiver-transmitter units or are inconvenient for quick adjustment and prevent the usual handling of the apparatus.

In the drawing—

Figure 1 illustrates the method of using a combination receiver-transmitter telephone unit when equipped with a supporting device constructed according to one form of my invention;

Fig. 2 is a perspective view of the arrangement shown in Fig. 1, upon an enlarged scale, illustrating the receiver-transmitter unit in dotted lines and the supporting device in full lines;

Fig. 3 is a longitudinal view of a combination receiver-transmitter telephone unit equipped with a supporting device constructed according to another form of my invention, said receiver-transmitter unit being shown in dotted lines and said supporting device in longitudinal section;

Fig. 4 is an end elevational view of the supporting device shown in Fig. 3, viewed from the right side of Fig. 3; and

Figs. 5 and 6 are cross-sectional views, illustrating details of construction of the supporting device shown in Fig. 2.

The combination receiver-transmitter telephone unit 1 comprises the receiver 2 and transmitter 3, connected by the shank 4 which is 55

designed to serve as a handle, thereby permitting the combination unit to be held in one hand and leaving the other hand of the user free for other purposes. While this type of telephone unit possesses certain well-recognized advantages over earlier constructions, principally in that it allows greater latitude of movement upon the part of the user, it nevertheless requires the use of one hand, since it is so formed that it is practically impossible to clamp it, with any degree of security, between the ear and shoulder and thereby leave both hands free, as illustrated in connection with my device in Fig. 1.

In the form of construction shown in Figs. 1 and 2, the wedge-shaped supporting device 5 is preferably formed as a cushion of compressible and resilient material, such as sponge-rubber, "soft" rubber, or felt, and may have a roughened or serrated shoulder-engaging surface 6. A plurality of pairs of clips 7—7 are employed for attaching the supporting device to the shank 4 of unit 1, the pairs being spaced apart to straddle the prongs of the usual telephone cradle-stand (not shown) and permit the unit to be placed in the proper manner upon said stand. As shown in the drawing, when the device 5 is in position upon the shank 4 of the unit 1, the thicker end-part of the device will be substantially beneath the receiver 2 and the tapered end-part is adjacent the transmitter 3, so that, when in use as shown in Fig. 1, the combination receiver-transmitter unit may be held securely upon the shoulder with the ear to the receiver and with the transmitter positioned the proper distance from the mouth of the user.

I do not wish to be limited to any particular construction of the clips 7—7. Where the supporting device is constructed of "soft" rubber, the clips may be cast as integral parts thereof, as shown in Fig. 2, the material being firm enough to cause them to frictionally grip the shank 4. Where sponge-rubber or felt is employed, they may be provided with pliable or spring metal cores or reinforcements. I have shown two such arrangements in Figs. 5 and 6, as illustrations of the many ways substantial clips may be used with such softer material. In Fig. 5, a flat plate 8 having laterally extending arms 9—9 is formed of pliable metal, such as sheet aluminum or soft brass, and is cast or molded in the softer material of which the device is formed, and completely covered thereby, while in Fig. 6, flat strips 14 of such pliable metal are passed transversely through slots 15 cut in the material, and the end-parts of the metal strips are covered or faced,

as at 16, with some softer material to prevent scratching of the shank 4 when the clips are bent therearound.

In the form of construction shown in Figs. 3 and 4, the supporting device comprises a cup-member 10 adjustably attached to the body 11 and the body is provided with two pairs of slips 12-12. I have illustrated the cup-member as attached by a hinge-pin 13, and it is to be understood that the hinge is in effect a tight stop-hinge, that is to say, the hinge attachment is designed to permit a limited adjustment of the cup-member to suit the convenience of the user and to retain such adjustment. Where the material employed is sufficiently pliable, as in the case of "soft" rubber, the hinge may be omitted and the neck-part of the cup-member cemented, or otherwise secured, to the body 11. I prefer the hinge connection, however, since it is more durable and provides for adjustment of a cup-member constructed of hard rubber or metal, where such material is preferred. Regardless of the material used, the adjustable cup-member constitutes a comfortable support for resting the unit upon the shoulder, and the body 11 occupies less space upon the shank 4, leaving a substantial portion thereof free for usual handling. I am well aware that the body 11 may be constructed to occupy less space upon the shank 4 than I have shown, and I do not desire to be limited in such respect.

I claim:

1. The combination, with a receiver-transmitter telephone unit having a receiver, a transmitter, and a shank connecting said receiver and transmitter, of a device attached to extend along the shank of said unit and project radially from the axis thereof, said device having a continuous shoulder-engaging base-portion extending lengthwise of said shank with one end of said base-portion terminating adjacent the receiver of said

unit, said device constituting a support for said unit to be positioned across and upon the shoulder of the user thereof, the angle at which said device projects radially from said shank and the position of said one end of said base-portion with respect to the receiver of said unit being such that said unit and said device may be held in such position solely by pressure of the ear of the user to the receiver of said unit.

2. The combination, with a receiver-transmitter telephone unit having a receiver, a transmitter, and a shank connecting said receiver and transmitter, of a cushion attached to extend along the shank of said unit and project radially from the axis thereof, said cushion having a shoulder-engaging surface extending lengthwise of said shank with one end of said surface terminating adjacent the receiver of said unit, said cushion constituting a support for said unit to be positioned across and upon the shoulder of the user thereof and frictionally held in such position by pressure of the ear of the user to the receiver of said unit.

3. The combination, with a receiver-transmitter telephone unit having a receiver, a transmitter, and a shank connecting said receiver and transmitter, of a shoulder-rest attached to extend along the shank of said unit and project radially from the axis thereof, said shoulder-rest having a base-portion with a continuous shoulder-engaging friction surface extending lengthwise of said shank and with one end of said base-portion terminating adjacent the receiver of said unit, said shoulder-rest constituting a support for said unit to be positioned across and upon the shoulder of the user thereof and frictionally held in such position by pressure of the ear of the user to the receiver of said unit.
